Primary Examiner — Selina Sikder(74) *Attorney, Agent, or Firm* — David A. Burge(57) **CLAIM**

I claim the ornamental design for a set of signalling switch and indicator light assembly, as shown and described.

DESCRIPTION

FIG. 1 is a top, front and left side perspective view showing my new design;

FIG. 2 is a top plan view of one part of the assembly thereof, shown separately for ease of illustration;

FIG. 3 is a front elevational view thereof, it being understood that a rear elevational view is a mirror image thereof;

FIG. 4 is a left side elevational view thereof;

FIG. 5 is a right side elevational view thereof;

FIG. 6 is a top plan view of the other part of the assembly thereof, shown separately for ease of illustration;

FIG. 7 is a front elevational view thereof;

FIG. 8 is a rear elevational view thereof; and,

FIG. 9 is a left side elevational view thereof, it being understood that a right side elevational view is a mirror image thereof.

Bottom views form no part of the claimed design, and are omitted from the drawings.
